UNITED STATES PATENT OFFICE.

MICHAEL BLOCK, OF SOUTH BOSTON, MASSACHUSETTS, ASSIGNOR TO AMERICAN CAN COMPANY, OF NEW YORK, N. Y., A CORPORATION OF NEW JERSEY.

CONTAINER.

Application filed April 27, 1921. Serial No. 465,023.

To all whom it may concern:

Be it known that I, MICHAEL BLOCK, a citizen of the United States, residing in South Boston, in the county of Suffolk and State of Massachusetts, have invented a new and useful Improvement in Containers, of which the following is a specification.

This invention relates in general to containers and more particularly to means for positively maintaining a hinged section or door in a side of the container in a predetermined position.

A principal object of the invention is the provision of a display container for crackers and the like, having a hinged front section and means at the top and bottom of the container adapted to hold said section in either its up or down position.

A further object of the invention is the provision in a container of this type of retaining means formed principally from the material regularly employed in the construction of an ordinary container and in no way decreasing the capacity or marring the appearance of said container.

A still further object of the invention is the provision of means whereby a glass or other frangible section of the container front may be easily moved to protected position, readily returned to closed or exposed position, and positively maintained in either position.

Still another object of the invention is the provision of devices for accomplishing the objects hereinbefore stated, which are of simple construction and add but little to the cost of producing an article of this character.

Numerous other objects and advantages of the invention will be apparent as it is better understood from the following description, which, taken in connection with the accompanying drawings, discloses a preferred embodiment thereof.

Referring to the drawings:

Fig. 1 is an elevational view of the front section of a container embodying my invention.

Fig. 2 is an enlarged vertical section taken substantially upon the line 2—2 of Fig. 1.

Fig. 3 is an enlarged elevation of the interior of the container front shown in Fig. 1.

Fig. 4 is an enlarged detail taken substantially upon line 4—4 of Fig. 3.

Fig. 5 is an enlarged detail taken substantially upon the line 5—5 of Fig. 3. 55

Upon the drawings, which provide an exemplification of my invention, I have shown the front section 11 of a container adapted especially for the display of crackers and other similar contents. In the upper part 60

of this section is an inset portion 12, herein shown as of semi-circular configuration, although it will be understood that the particular design is unimportant from the stand-point of the invention. In the lower part 65

of the front section 11 is an opening in front of a glass portion 13 appearing from the exterior to be a rigidly set window. It is shown 70

as of generally oblong formation but manifestly may assume any desired form or size. The front is joined to the other walls of the container in any preferred manner, being shown in Fig. 1 as engaged by an upturned flange 14 of the bottom, and as being integral with the sides. A cover 15 is hinged 75

upon the container body and is adapted to be maintained in closed position by frictional engagement of a depending front flap or flange 16 with the front of the container. This flange is shown on the drawings as being beaded at its extremities 17 to permit ready lifting of the top to open position. 80

By reference to Fig. 3 the internal arrangement of the front sections hereinbefore referred to may be observed. A lower section or door 18 in which the glass window 13 is secured, is hinged as indicated at 19 to the front of the body, for which purpose the latter is provided with a vertically arranged 85

piece 28 extending across the front (Fig. 3). This hinge, as shown, is formed of alternate beaded segments 21 and 22 in the door section and the body front, having a pin or rod 23 extending therethrough. 90

At the bottom of the container and near the front are upstanding projections 24 formed by inwardly indenting the material of the bottom. These projections are of such height as to permit the lower edge 25 of the section 18 to be forced past them and yet to retain the door positively against backward movement, except in the event that positive pressure is applied to it to move it 95

inwardly. In this manner the door is held in closed position when desired and inadvertent or accidental opening or swinging inwardly is prevented. 100

However, if it is desired to maintain the door in open position in order to protect the glass when the container is being shipped empty, it may be swung upwardly and held in raised position by depending catches 26, which are formed by deforming or indenting a horizontal flange which extends inwardly from the front section 11. This flange is turned over upon itself and between the folds thereof is contained a brace or reinforcing member 27, this member being bent to conform to the configuration of the front end flange just described, and having a portion lying against the upper front section 11. Referring to Figs. 2 and 4, it will be noted that the edge 25 of the door 18 is adapted to be forced past the catches 26, inside the container top, and to be frictionally engaged thereby to prevent inward movement excepting through the application of positive pressure. Further outward movement is prevented by the vertical portion 28 of the front, to which the door is hinged. Thus the door is maintained in rigid upstanding position and the container may be freely handled without jarring it out of place, or causing it to drop to closed position. The snaps or catches 26 manifestly may be of varying width and number, the showing of the drawings in this respect being merely an apt illustration of the principle of the invention.

It will be understood that the exterior of the front 11 is formed of a single sheet of metal 29 and that the inset section 12 and the opening in front of the window 13 have about their peripheries suitable offsets or beaded portions 31 and 32 adapted to present a pleasing appearance. The glass in the door 18 may be secured in any preferred manner, it, however, being shown in the present instance as being embraced by flanges 33 of the metal portion of the door, said flanges being turned over upon the rear portion of the door at sufficient distance to permit engagement of the glass section referred to. At the bottom of the front metal sheet is a bead or corrugation 34 extending nearly the width of said section and rounded at the ends, this being for the purpose of adding to the pleasing appearance of the container.

It is thought that the invention and many of its attendant advantages will be understood from the foregoing description, and it will be apparent that various changes may be made in the form, construction and arrangement of the parts without departing from the spirit and scope of the invention, or sacrificing all of its material advantages, the form hereinbefore described being merely a preferred embodiment thereof.

I claim:

1. A container for crackers and the like, comprising a body and a front having a

hinged display section therein depending from its hinge towards the bottom of the container and adapted to be swung upwardly within said container, and fixed projections or catches on the inside of the container top and adapted to frictionally engage said display section to hold it in its up or open position. 70

2. A container for crackers and the like, comprising a body and a front having a hinged display section therein depending from its hinge towards the bottom of the container and adapted to be swung upwardly within said container, and fixed projections or catches at the top and bottom of 80 said container, the one being adapted to frictionally engage said hinged section to hold it in its up or open position, and the other being adapted to so engage it to maintain it in its down or closed position. 85

3. A container for crackers and the like, comprising a body and a front having a hinged display section therein depending from its hinge towards the bottom of the container and adapted to be swung upwardly within said container, and a plurality of projections or catches at the top and bottom of said container, the top ones being adapted to frictionally engage said hinged section to hold it in open position, and those at the bottom being adapted to so engage it to maintain it in closed position. 90

4. In a container for crackers and the like, a hinged display section depending from its hinge towards the bottom of the container and adapted to be swung upwardly within the container and stationary spring catches at the top and bottom of said container adapted to engage said hinged section to maintain it respectively in open and closed position. 100 105

5. In a container for crackers and the like, a hinged display section depending from its hinge towards the bottom of the container and adapted to be swung upwardly within the container and protuberances formed at the top and bottom on the interior of said container for frictionally engaging said hinged section to maintain it respectively in open and closed position. 110 115

6. In a container for crackers and the like, a hinged display section depending from its hinge towards the bottom of the container and adapted to be swung upwardly within the container, sheet metal protuberances formed at the top and bottom on the interior of said container for frictionally engaging said hinged section to maintain it respectively in open and closed position. 120 125

7. In a container for crackers and the like, a hinged display section depending from its hinge towards the bottom of the container and adapted to be swung upwardly within the container, and inward indentations in the material of the top and bottom 130

of the container for engaging said hinged section to maintain it respectively in open and closed position.

8. In a container for crackers and the like, 5 a hinged display section depending from its hinge towards the bottom of the container and adapted to be swung upwardly within the container, and inward indentations in the material of the top and bottom 10 of the container for engaging said hinged section to maintain it respectively in open and closed position, said indented portion at the top being of double thickness and embracing a strengthening member fitting 15 against the material of the front and the top at its line of bend.

9. In a cracker or like container, a sheet metal display wall having an opening, and a transparent display member hinged to said 20 wall and swingable inwardly from its display position and upwardly to a protected position behind a solid part of said wall.

10. In a cracker or like container, a sheet

metal display wall having an opening, and a display section having a glass and hinged to said wall and swingable inwardly from its display position to a protected position behind a solid section of said wall and in parallel relationship with said solid section. 25

11. In a cracker or like container, a sheet 30 metal display wall having an opening, a display section hinged to said wall and having a glass and swingable inwardly from its display position to a protected position behind a solid section of said wall, and means 35 for holding said display section in the protected position.

12. A display container having a sheet 40 metal wall formed with a display opening and a continuous closed portion, and a display door having a glass and hingedly connected with said wall and swingable to a position behind said opening and to a protected position behind said closed portion of the wall.

MICHAEL BLOCK.
